UNITED STATES PATENT OFFICE.

FREDERICK W. PENDERGAST, OF CAMBRIDGE, MASSACHUSETTS.

CHIMNEY-HEATER.

1,343,745.

Specification of Letters Patent. Patented June 15, 1920.

Application filed October 11, 1919. Serial No. 329,901.

To all whom it may concern:

Be it known that I, FREDERICK W. PENDERGAST, a citizen of the United States, residing at Cambridge, in the county of Middlesex and State of Massachusetts, have invented new and useful Improvements in Chimney-Heaters, of which the following is a specification.

This invention relates to heat-economizing means adapted to utilize waste heat passing up a chimney. The invention has for its object to provide a simple and effective heat-economizing means or chimney-heater adapted to be conveniently installed in a chimney and conduct water through a portion of the chimney flue in such manner as to cause the water to absorb a considerable portion of the waste heat, the structure being adapted to be connected with a heat radiator in an adjacent room.

The invention consists in the improvements which I will now proceed to describe and claim.

Of the accompanying drawings forming a part of this specification,—

Figure 1 is a side view showing a portion of a chimney equipped with a heater embodying the invention, and a radiator connected with the heater.

Fig. 2 is a sectional view of the chimney, on line 2—2 of Fig. 1, and an edge view of the heater.

Fig. 3 is a section on line 3—3 of Fig. 2.

Fig. 4 is a view similar to a portion of Fig. 1, the door shown by Fig. 1 being removed.

Fig. 5 is a perspective view of the heater detached from the chimney, and from the holding means hereinafter described.

Fig. 6 is a fragmentary section on line 6—6 of Fig. 7.

Fig. 7 is a fragmentary section on line 7—7 of Fig. 4.

Fig. 8 is a fragmentary sectional view on line 8—8 of Fig. 2.

Fig. 9 is a fragmentary sectional view on line 9—9 of Fig. 2.

Fig. 10 is a fragmentary sectional view on line 10—10 of Fig. 2.

The same reference characters indicate the same parts in all of the figures.

In the drawings, 12 represents a chimney, in one side of which is formed an opening 13, said opening being vertically elongated, and its width being substantially equal to the width of the chimney flue.

My improved heater is embodied in a structure adapted to be inserted in the opening 13, and suitably secured therein. Said structure includes a plurality of narrow 60 elongated water conduits 14, having parallel substantially vertical sides, a lower transverse header 15, communicating through openings 16 with the lower ends of the water conduits 14, and a transverse upper header 65 17 communicating through openings 18 with the upper ends of the water conduits.

As best shown by Figs. 6 and 7, the water conduits 14 are provided with flanges 19, which bear on the external surfaces of the 70 headers, and are brazed or otherwise attached thereto to form water-tight joints around the openings 16 and 18.

The headers 15 and 17 may be connected with a radiator 22 by pipes 20 and 21, communicating with the radiator and with the lower header 25, and a vertical pipe 23 connecting the two headers. I do not limit myself to this arrangement of connections, my object being to so connect the water conduits 14 with the radiator 22, that relatively hot water will flow from the water conduits to the radiator, and cooler water will flow from the radiator to the water conduits.

It will be seen by reference to Fig. 6, that 85 water is adapted to flow from one of the headers into the water conduits 14, and from said conduits into the other header.

The water conduits 14 are spaced apart as best shown by Figs. 3 and 5, so that they 90 form sides of flue portions, through which heated products of combustion pass vertically, so that water in said conduits is heated.

I prefer to connect the inner edges of conduits by a plate 14^a, which bears on the inner side of the chimney flue, and may be supported by a fixed ledge 10, (Fig. 2).

The water conduits 14 are separated from each other at their forward edges, so that 100 a flue-cleaning brush may be readily inserted between the conduits and moved vertically, to remove soot from their external surfaces.

To provide for the convenient installation 105 of the heater in the chimney 13, I provide supporting means attachable to the chimney, and provided with a movable closure for the opening 13, said supporting means being suitably attached to portions of the heater 110 structure.

As here shown, I have embodied the sup-

porting means in a frame 27, formed to surround the opening 13, and provided with a flange 28, formed to bear on the outer face of the chimney. The top and bottom members of the frame may be provided with ears or brackets 29, suitably engaged with the headers 15 and 17.

To the frame is connected by hinges 30, a door 31, formed to cover the opening surrounded by the frame. Said door, as shown by Figs. 1 and 2, is preferably provided with an offset portion 31^a at its lower end, to accommodate the pipes 20 and 21. The flange 28 may be secured to the chimney by bolts 33, or otherwise.

It will now be seen that the described heater is adapted to be conveniently installed in a chimney, without objectionably obstructing the flue.

The only parts of the heater that project into the flue are the relatively thin water conduits 14, which are spaced apart by portions of the flue, as above stated, the headers 15 and 17 being outside the flue and in the chimney opening.

It will also be seen that the heater is adapted to be readily cleaned, when the door 31 is opened.

As shown by the fragmentary sectional views, Figs. 8, 9 and 10, each water conduit 14 includes vertical side walls 14^b, which are parallel with each other, and form the opposite sides of a narrow water-conducting space, narrow vertical walls 14^c connecting the side walls at the forward and rear edges of the conduit, and narrow horizontal walls 14^d connecting the side walls at the upper and lower ends of the conduit.

The side walls 14^b of each conduit are preferably supported laterally by spacing members 35, interposed between said walls, and riveted or otherwise attached thereto, said spacing members being arranged to

permit a free circulation of water through the conduit. As shown by Figs. 9 and 10, 45 the spacing member is a metal strip, extending from a point about six inches above the lower end of the conduit, to a point about six inches below the upper end, water being adapted to flow across the ends of the strip. 50

The conduits 14 are preferably made of sheet metal, such as copper.

The heater may be provided with a suitable safety valve, adapted to release steam pressure, and to automatically close when 55 the pressure is suitably reduced.

I claim:

In combination with a chimney having an opening in one side above its lower or intake portion, an attachment comprising a 60 frame surrounding said opening, a movable closure for said frame forming, when closed, a portion of the chimney wall, means attaching the frame to the chimney, and a heat economizing structure attached to and 65 supported by said frame and projecting therefrom into the chimney flue, said structure including a plurality of substantially vertical conduits spaced from each other to permit the passage, between adjacent conduits, of products of combustion from the flue portion of the chimney below the structure, to the flue portion above the structure, and fluid-conducting connections between 70 said conduits, having means for connection 75 with a heat radiator, the space between said conduits being exposed, to permit the cleaning of the conduits, when said closure is displaced.

In testimony whereof I have affixed my 80 signature.

his
FREDERICK W. X PENDERGAST.
